SOUND TRANSLATING DEVICE

Albert E. Woodruff, Oak Park, Ill., assignor to
Associated Electric Laboratories, Inc., Chicago,
Ill., a corporation of Delaware

Application May 26, 1938, Serial No. 210,179

2 Claims. (Cl. 179—119)

The present invention relates to sound translating devices and more particularly to a magnetic unit adapted to be utilized in a telephone transmitter or receiver.

In a sound translating device a magnetic unit is provided which conventionally comprises a field structure including a substantially U-shaped permanent magnet having two outwardly extending legs, each of which is individually associated with two spaced-apart pole pieces formed of magnetic material. The pole pieces are arranged in two sets, the pole pieces of each set being directed toward each other, and the pole faces of each set of pole pieces being arranged in spaced-apart relation in order to receive therebetween the opposite ends of a pivotally mounted armature formed of magnetic material. One end of the pivotally mounted armature is connected to a diaphragm, and a winding or voice coil carried by a winding spool arranged between the two sets of pole pieces is electromagnetically coupled to the armature. In the case of a telephone transmitter, the vibrations of the diaphragm, produced by the sound to be transmitted, cause the ends of the armature to vibrate between the pole faces of the two sets of pole pieces, thereby to generate a corresponding signal voltage. In the case of a telephone receiver, the signal current passing through the voice coil causes the ends of the armature to vibrate between the pole faces of the sets of pole pieces, thereby to reproduce at the diaphragm a corresponding sound. The field structure of a magnetic unit of this type is usually carried by a supporting plate, one leg of the permanent magnet being arranged in abutting engagement with the plate and secured thereto. Also, the magnetic unit is provided with an enclosing casing secured to the supporting plate in order to exclude dust and moisture therefrom. While a magnetic unit of this type is satisfactory in operation, it requires a larger enclosing casing and is of larger size than is desirable.

Accordingly, it is an object of the present invention to provide, in a sound translating device, an improved magnetic unit of the type described which is of compact and rugged construction, and which embodies an enclosing casing of relatively small size.

Another object of the invention is to provide, in a sound translating device, a magnetic unit of the type described which includes a field structure and a supporting plate, and which embodies an improved arrangement for mounting the field structure on the supporting plate.

In general, the objects as set forth above are attained in accordance with the present invention by providing, in a sound translating device, a magnetic unit of the character noted comprising a field structure including two outwardly extending field members arranged in spaced relation, pole pieces carried by the field members which are directed toward each other and arranged in spaced relation in order to receive therebetween a movable armature, a supporting element provided with an outwardly extending recess therein, one of the field members being arranged in the recess in the supporting element in order to reduce the distance between the other field members and the supporting element, and means for securing the field structure to the supporting element.

In accordance with another feature of the invention, the field structure comprises a U-shaped permanent magnet having two outwardly extending legs arranged in spaced relation, each leg of the magnet being secured to a substantially U-shaped field element having two legs arranged in spaced relation, corresponding legs on the field elements being directed toward each other and constituting pole pieces arranged in two sets. Means are provided for securing the field elements together with the pole faces of each of the sets of pole pieces arranged in spaced relation and for securing the field elements to the supporting element adjacent the recess therein. A winding spool is arranged between the two sets of pole pieces and carries an armature pivotally mounted thereon, the opposite ends of the armature being arranged between the pole faces of the two sets of pole pieces. One of the legs of the U-shaped magnet is arranged in the recess in the supporting element in order to reduce the distance between the other leg of the magnet and the supporting element. An enclosing casing is provided for the magnet unit which is secured to the supporting element, one wall of the enclosing casing being arranged closely adjacent the other leg of the U-shaped magnet.

The novel features believed to be characteristic of the invention are set forth with particularity in the appended claims. The invention, both as to its organization and method of operation, together with further objects and advantages thereof, will best be understood by reference to the following specification taken in connection with the accompanying drawing in which Figure 1 is a side elevational view, partly in section, of a magnetic unit for a sound translating device and embodying the present invention; Fig.

2 is an end elevational view, partly in section, of the magnetic unit of Fig. 1; Fig. 3 is an enlarged plan view of a portion of a winding spool and armature assembly embodied in the magnetic unit; and Fig. 4 is a sectional view of the complete assembly taken along the line 4-4 of Fig. 3.

Referring now more particularly to Figs. 1 and 2 of the drawing, there is illustrated a magnetic unit 10, adapted to be utilized in a sound translating device in the form of a telephone transmitter of the sound-powered type or a telephone receiver, which comprises a magnetic field structure including a substantially U-shaped permanent magnet 11 having two outwardly extending field members or legs 12 and 13 arranged in spaced relation, and two substantially U-shaped field elements 14 and 15 formed of magnetic material. The field elements 14 and 15 are each provided with two legs 16, 17 and 18, 19, respectively, arranged in spaced relation, corresponding legs on the field elements being directed toward each other and constituting pole pieces arranged in two sets. The pole pieces 16 and 18 constitute one set and the pole pieces 17 and 19 constitute another set. The field elements 14 and 15 are provided with outwardly extending lugs 20, 21 and 22, 23, respectively, and are secured together with the pole faces of each set of the pole pieces arranged in spaced relation by an arrangement comprising two bushings 24 and 25 arranged between the lugs 20, 22 and 21, 23, respectively, and two screws 26 and 27 extending through aligned openings formed in the lugs and bushings. The screw 26 extends through aligned openings formed in the lugs 20 and 22 and the bushing 24; and the screw 27 extends through aligned openings formed in the lugs 21, 23 and the bushing 25. The outer ends of the screws 26 and 27 are arranged in threaded engagement with openings provided in a supporting element or plate 28, thereby securely to retain the field structure to the plate 28.

The leg 12 of the magnet 11 engages the field element 14 and is secured thereto by an arrangement comprising a strap 29 embracing a portion of the leg 12 adjacent the outer end thereof, the opposite ends of the strap 29 being clamped between the heads of the screws 26 and 27 and the adjacent lugs 20 and 21, respectively, on the field element 14. Preferably, the opposite ends of the strap 29 are provided with openings therein, through which the screws 26 and 27 extend. The leg 13 of the magnet 11 engages the field element 15 and is secured thereto by a screw 30 extending through an opening formed in the leg 13 and threaded into an opening formed in the field element 15. The plate 28 is provided with an outwardly extending recess 28a therein which receives the leg 13 of the magnet 11, the inner surface of the leg 13 engaging the adjacent surface of the field element 15 and being arranged substantially in the plane of the inner surface of the plate 28. This arrangement substantially reduces the distance between the inner surface of the plate 28 and the outer surface of the leg 12 of the magnet 11, thereby reducing the over-all height of the field structure an appreciable amount.

A winding spool and armature assembly 31 is arranged between the two sets of pole pieces 16, 18 and 17, 19. Preferably, the winding spool and armature assembly 31 is of the construction of that disclosed and claimed in the copending application of Albert E. Woodruff, Serial No. 209,803, filed May 24, 1938; and, as best shown in Figs.

3 and 4, comprises a winding spool 32 formed of insulating material such as "Bakelite" and an armature 33 formed of flat magnetic stock.

The winding spool 32 is split longitudinally and comprises complementary upper and lower sections 32a and 32b, respectively, of similar construction. Each of the sections includes a body portion 34 carrying two spaced-apart winding retaining heads 35. The wall of the body 34 of the lower section 32b is provided with a longitudinally extending recess 34a therein which is disposed adjacent the joint between the upper and lower sections 32a and 32b, respectively. The wall of the body of the upper section 32a is substantially flat adjacent the joint between the upper and lower sections 32a and 32b, respectively. The armature 33 is provided with a longitudinally extending operating lug 36 and two transversely extending spaced-apart lugs 37 intermediate the ends thereof. Each of the lugs 37 projects from one side of the armature 33 and is provided with a head 37a connected by a length 37b to the armature 33, the length 37b being of reduced cross-sectional area. The armature 33 is arranged in the recess 34a provided in the wall of the body 34 of the lower section 32b, the armature 33 being retained in position by spaced-apart and aligned recesses 34b provided in the body 34 of the lower section 32b and receiving the heads 37a on the lugs 37. The lugs 37 are retained in the recesses 34b provided in the body 34 of the lower section 32b by two mounting clips 38. Each of the clips 38 is of substantially U-shape comprising two flanges 39 and 40, the flange 40 being provided with three spaced-apart fingers 40a, 40b and 40c. Each of the clips 38 embraces one side of the body 34 of the lower section 32b, the clip 38 being retained in place by the clamping action between the two outside fingers 40a and 40c, and the flange 39 upon the body 34. The intermediate finger 40b on the clip 38 engages the head 37a on one of the lugs 37, thereby rigidly securing the lug to the body 34 of the lower section 32b. The clips 38 mount the armature 33 on the body 34 of the lower section 32b for vibratory movements about an axis extending between the lugs 37 transversely of the winding spool 32.

In constructing the assembly 31, the armature 33 is brought into position with respect to the recesses 34b provided in the body 34 of the pre-formed lower section 32b of the winding spool 32 and lowered into place, the heads 37a on the lugs 37 being received in the recesses 34b formed in the body 34. The clips 38 are then placed upon the sides of the body 34, and the outside fingers 40a and 40c and the flange 39 are bent into engagement with the body 34 in order securely to fasten the clips 38 thereto. The armature 33 is then aligned and the intermediate fingers 40b are then bent into engagement with the heads 37a on the lugs 37 in order securely to retain the armature 33 in position. The pre-formed upper section 32a is then brought into superimposed relation with the lower section 32b to complete the assembly 31, the upper and lower sections 32a and 32b, respectively, being retained together by the field structure of the magnetic unit in any suitable manner.

The walls of the body 34 of the upper and lower sections 32a and 32b are spaced a short distance from the armature 33, and the ends of the armature 33 project through the winding spool 32; these ends of the armature being protected against injury by projections 42 provided on the ends of the sections 32a and 32b. Thus, the com-

posite body of the winding spool 32 is hollow, and is provided with a wall surrounding a narrow opening extending longitudinally therethrough, the armature 33 being arranged within the opening in the body. The armature 33 is supported by the lugs 31 for vibratory movements out of contact with the wall of the body and about an axis extending between the lugs 31 transversely of the winding spool 32. When the armature 33 is moved from its normal position, the lugs 31 are subjected to torsional strains, these strains being localized in the lengths of reduced cross-sectional areas 31^b of the lugs 31. This torsional mounting of the armature 33 is very advantageous as it causes the armature to be deflected an amount precisely corresponding to the force exerted on the operating lug 36, the deflection of the armature 33 being directly proportional to the force exerted upon the operating lug 36 over a wide range.

A winding, not shown, is arranged about the body 34 between the winding retaining heads 35 of the winding spool 32 and one end 33^a of the armature 33 is disposed between the oppositely disposed pole faces of the set of adjacent pole pieces 17 and 18, while the other end 33^b of the armature 33 is disposed between the oppositely disposed pole faces of the set of adjacent pole pieces 16 and 18. The operating lug 36 on the armature 33 is provided with an opening therein in which one end of a rod 43 is secured, the rod 43 extending through an opening formed in the leg 13 of the magnet 11. The other end of the rod 43 is secured to a sound-wave-responsive diaphragm 44 by an arrangement comprising a pair of nuts 44^a. The periphery of the diaphragm 44 is clamped between the outer surface of the supporting plate 28 and an annular ring 45 secured to the plate 28. An arrangement comprising a moisture-proof washer 46 interposed between the diaphragm 44 and the supporting plate 28 and a moisture-proof washer 47 interposed between the diaphragm 44 and the ring 45 is provided for sealing the interior of the casing of the magnetic unit against the entrance of dust and moisture thereinto. The magnetic unit is also provided with an enclosing casing 48 which is secured to the supporting plate 28 by an arrangement comprising an annular ring 49, which effectively seals the interior of the casing of the magnetic unit against the entrance of dust and moisture thereinto.

Normally, the armature 33 occupies a position wherein the opposite ends thereof are disposed intermediate the adjacent pole faces of the two sets of pole pieces and is adapted to be vibrated therebetween. When the magnetic unit is utilized in a telephone transmitter of the sound-powered type, the movement of the armature 33 is controlled in accordance with the vibratory movements of the diaphragm 44, the vibratory movements of the diaphragm 44 corresponding to the vibrations of the air produced by a sound to be transmitted. When the magnetic unit is utilized in a telephone receiver, the movement of the armature 33 is controlled in accordance with the signal currents traversing the voice coil electromagnetically coupled therewith, thereby to cause corresponding vibratory movements of the diaphragm 44 and the consequent reproduction of the transmitted sound. As the armature 33 is moved in a clockwise direction about its pivot, as viewed in Fig. 1, the magnetic field of the field structure traverses a path extending from the north pole of the permanent magnet 11 by way

of the leg 12, the pole piece 16 of the field element 14, the armature 33, the pole piece 18 of the field element 15 and the leg 13 to the south pole of the permanent magnet 11. On the other hand, when the armature is moved in a counterclockwise direction about its pivot, the magnetic field of the field structure traverses a path extending from the north pole of the permanent magnet 11 by way of the leg 12, the pole piece 17 of the field element 14, the armature 33, the pole piece 16 of the field element 15 and the leg 13 to the south pole of the permanent magnet 11. Thus, during the vibratory movement of the armature 33, the magnetic field of the field structure traverses the armature 33 in opposite directions, in a well-known manner.

Due to the arrangement of the leg 13 of the magnet 11 in the recess 28^a in the supporting plate 28, the distance between the inner surface 20 of the supporting plate 28 and the outer surface 25 of the leg 12 of the magnet 11 is substantially reduced, thereby effecting a considerable reduction in the over-all height of the magnetic unit. Due to this reduction in the over-all height of the magnetic unit, the enclosing casing 48 thereof may be constructed considerably smaller and the inner wall thereof may be arranged closely adjacent to the outer surface of the leg 12 of the magnet 11 without interfering with the operation 30 of the magnetic unit. Moreover, the particular arrangement for securing the field elements 14 and 15 in spaced-apart relation and to the supporting plate 28, and the arrangement for securing the magnet 11 to the field elements 14 and 15 are very advantageous, as they render the magnetic structure of rugged and compact construction. Finally, these arrangements embodied in the magnetic unit are productive of substantial 35 manufacturing economies.

While there has been described what is at present considered to be the preferred embodiment of the invention, it will be understood that various modifications may be made therein, and it is contemplated to cover in the appended claims all such modifications as fall within the true spirit and scope of the invention.

What is claimed is:

1. In a sound translating device, a field structure including two field elements secured together and provided with cooperating pole pieces, a pivotally mounted armature operatively associated with said pole pieces, a substantially U-shaped magnet having two outwardly extending legs arranged in spaced relation and embracing said field structure, means for securing the legs of said magnet to said field structure, thereby to support said magnet, a supporting plate having a slot provided therein, said field structure being arranged adjacent the inner side of said supporting plate, whereby one of said field elements overlies the slot provided therein, means for securing said one field element to the inner side of said supporting plate on opposite sides of the slot provided therein, thereby to support said field structure, one of the legs of said magnet and the inner side of said supporting plate being arranged in spaced relation and the other leg of said magnet being arranged in the slot provided in said supporting plate, thereby to minimize the distance between the one leg of said magnet and the inner side of said supporting plate, and a casing secured to said supporting plate and enclosing said field structure and said magnet, said casing having an end wall arranged closely adjacent the one leg of said magnet.
2. In a sound translating device having a dia-

phragm, a field structure including two field elements secured together and provided with co-operating pole pieces, a pivotally mounted armature operatively associated with said pole pieces, a substantially U-shaped magnet having two outwardly extending legs arranged in spaced relation and embracing said field structure, thereby to support said magnet, a supporting plate having a slot provided therein, said field structure being arranged adjacent the inner side of said supporting plate, whereby one of said field elements overlies the slot provided therein, means for securing said one field element to the inner side of said

16 supporting plate on opposite sides of the slot provided therein, thereby to support said field structure, one of the legs of said magnet and the inner side of said supporting plate being arranged in spaced relation and the other leg of said magnet being arranged in the slot provided in said supporting plate, thereby to minimize the distance between the one leg of said magnet and the inner side of said supporting plate, and a link passing through a hole in said other leg connecting the armature and the diaphragm.

ALBERT E. WOODRUFF.
